UNITED STATES PATENT OFFICE.

EUGENE M. COLE, OF CHARLOTTE, NORTH CAROLINA.

GUANO DISTRIBUTOR.

Application filed July 13, 1926. Serial No. 122,109.

My invention relates to guano distributors and more especially to guano distributors in which the bottom of the hopper for holding the guano is adapted to be oscillated and centrifugal force applied to the guano to more perfectly distribute the same.

Another object of my invention is to provide a guano distributor in which the bottom of the hopper is entirely separated from the hopper and the degree of separation is capable of being adjusted, together with means for imparting an oscillatory motion to the hopper bottom.

Another object of my invention is to provide a guano distributor having a hopper with an open lower end with a circular bottom mounted below the open end and pivoted at its center for oscillation and adapted to be adjusted with respect to the lower end of the hopper, together with means associated with one of the ground wheels for imparting an oscillatory motion to the hopper bottom with means associated with the hopper bottom and with the frame of the distributor to suddenly arrest the oscillatory motion of the hopper bottom.

Another object of my invention is to provide an oscillatory bottom for hoppers in guano distributors in which oscillation is imparted thereto by knocker means associated with one of the ground wheels of the distributor.

Another object of my invention is to provide a guano distributor with a hopper having an open lower end with an oscillating bottom member mounted beneath the open end of the hopper and capable of vertical adjustment with respect to the lower end of the hopper.

Some of the objects of invention having been stated, other objects will appear as the description proceeds.

I have shown a preferred embodiment of my invention in the annexed drawings, in which

Figure 1 is a perspective view of my guano distributor;

Figure 2 is a bottom plan view of my guano distributor showing the means for imparting oscillatory and centrifugal force to the adjustable bottom of the hopper;

Figure 3 is an enlarged detail bottom plan view of the central portion of Figure 2;

Figure 4 is a cross-sectional view, partly in section, taken along the line 4—4 in Figure 3;

Figure 5 is a plan view of the adjusting rack for the lever 48;

Figure 6 is an enlarged detail elevation of the means which engage the cogs on the wheel 15 for imparting oscillatory motion to the bottom member of the hopper.

A brief description of the drawings having been given, a detailed description of the same will now follow in which like reference characters indicate corresponding parts throughout the drawings.

The numerals 10 and 11 indicate the side members of a substantially V-shaped frame, which has draft means 12 located between the forward ends of the said side members, and rearwardly of the draft means the downwardly projecting brackets 13 and 14 are secured to the inner sides of the side members, and in the lower ends of the said brackets is mounted the ground wheel 15, the said ground wheel having cogs 16 projecting at regular intervals from one side thereof.

Secured to the forward portions of said side members are the handle members 17 and 18 which are supported on the rear ends of the side members by the upright members 19 and 20. Plow carrying arms 21 and 22 are secured to the rear portions of the members 10 and 11 and these carry the plows 23. Pivotedly secured to the plow carrying arms are the wheel carrying assemblies 24 and 25 to which are rotatably secured the wheels 26 and 27.

A guideway 28 is secured between the handle members in which the lever 29 is adapted to be adjusted by means of the adjusting mechanism 30 and is held in elevated position by the projection 31 in the guideway, the said lever 29 being forked and the lower ends of the forks being rigidly secured in the wheel carrying assemblies 24 and 25.

A hopper 35 is rigidly secured to the frame between the handle members 17 and 18 and is also secured to the side members 10 and 11 by means of the iron members 36 and 37, the said members 36 and 37 being secured to the side members by the bolts 38 and 39, and on these same bolts is secured the supporting member 40 which serves to support the oscillatory bottom member 50, as will presently appear. Secured to the member 40 by means of bolts 41 and 42 is the circular hollow cam member 43 which has three inturned cams 44 thereon which slope downwardly around

the member 43 and support the circular member 45 by means of projections 46 extending outwardly from the member 45 and resting on the cams 44. Projections 47 extend outwardly from the member 45 and fit just below the lower surface of the cams 44. Two of the projections 46 have extensions 46' thereon, on which the ends of the forked adjusting lever 48 fit loosely. The member 45 has a hole in its upper central portion which is adapted to receive the bolt 49 for loosely and rotatably securing the oscillatory bottom member 50 to the member 45, the said bottom member 50 having projections 51 on its upper surface which are adapted to stir the guano in the hopper 35 before the same is distributed.

Rearwardly from the bottom member 50 and associated parts is the arcuate adjusting member 55 which is secured to the cross-piece 56 which extends from one of the side members to the other. This arcuate member 55 has an arcuate slot 57 therein in which the adjusting means 58 for the lever 48 is adapted to fit while in adjusted position. The adjusting means 58 is adapted to be secured at any desired point along the slot 57 by means of a set screw 59, and a notch 60 is located in the upper surface of the means 58 in which the lever 48 is adapted to rest while in adjusted position. By placing the lever 48 and adjusting means in the position shown in Figures 1 to 5 the oscillatory bottom member is adjusted at its lowest position, and when the lever is swung in the opposite direction as indicated by the arrow 61 in Figure 2 the projections 46 will travel up the inclined cams 44, and the bottom member 50 will be raised towards the lower open end of the hopper 35.

Rigidly secured to the lower side of the oscillatory bottom member 50 is the member 62 which has an eye member 63 in which the rod 64 is adapted to be hooked. This member 62 has a projection 65 which extends beyond the periphery of the bottom 50 and is adapted to press against the lever 66 when the said lever is pulled rearwardly at its upper end. This lever 66 is pivoted as at 67 and is adjusted by set screw means 68 secured to the upper end of the lever and penetrating a slot 69 in the member 52 which is secured to the hopper 35.

The rod 64 extends forwardly and is connected to an eye 71 in the pivoted arm 72, the arm 72 being pivoted on the bolt 32 to the member 74 which is secured to the side member 10 by the bolts 74' which fit into the holes 74" in the member 74 and pass through the side member 10. The pivoted arm 72 has an adjustable lug 73 secured to the lower end of the same by means of the bolt 33 penetrating the elongated vertical slot 34, which permits the lug to be adjusted vertically. This lug engages the cogs 16 on the wheel 15, and by

the cooperation of the coiled spring 76 and the rod 64 imparts oscillatory motion to the member 50.

The member 75 is adjustably secured to the side member 10 by the bolt 75' fitting in an elongated slot in the member 75, and in the forward end of the member 75 is secured the coiled spring 76, the other end of the coiled tension spring being secured in the eye 72" in the pivoted arm 72. This tension spring normally pulls the pivoted arm rearwardly and causes the lug 73 to engage the cogs 16 on the wheel 15.

Encircling the bottom member 50 and associated parts is the shield member 80 which is secured to the side members 10 and 11, and has a notch 81 therein through which the rod 64 passes.

The method of operation of my guano distributor is as follows:

The lever 48 is placed at the opposite end of the slot as shown in the drawings and thus the bottom member 50 is adjusted at its closest position to the lower end of the hopper 35, and the hopper is filled with guano or other material desired to be distributed. The lever 66 is pulled rearwardly and the lower end thereof engages the projection 65 and imparts a slight rotation to the bottom member 50, and thus the rod 64 is pushed forwardly against the pull of the coiled tension spring 76, and the arm 72 is swung forwardly and the lug 73 is brought to a position where it will not engage any one of the cogs 16, and thus arranged the oscillating means will not operate and with the lever 29 in the position shown in Figure 1 the device may be transported from place to place without distributing any guano.

When it is desired to operate the distributor the lever 48 and the adjusting means 58 are moved in the direction indicated by the arrow A in Figure 3 to any desired position, depending on the number of pounds per acre it is desired to distribute, and the lever 66 is adjusted forwardly at its upper end and the spring 76 pulls the lug 73 into position where it will engage the cogs 16, also pulling the rod 64 and the member 62 rearwardly. As the ground wheel 15 revolves the lug 73 and the pivoted arm 72 are pressed forward and after passing one cog 16 will be suddenly pulled rearward by the spring 76 and will suddenly engage the next successive cog, and while being pulled rearwardly will force the rod 64 rearward and the bottom member 50 will be oscillated, and when the lug 73 strikes the next cog a sharp jar will be imparted to the whole machine and the guano will be jarred off the bottom member 50 and will also be thrown off by the centrifugal force applied thereto. The amount of oscillation may be adjusted by the position of the lower end of the lever 66, as when it is entirely placed

out of the path of the projection 65 it will have a full swing until the lug 73 touches the next cog, but when the lever is so adjusted as not to permit the lug 73 to be pulled entirely back against the next cog, then the projection 65 will strike the lower end of the lever 66 and impart a jar to the bottom member 50 and also to the hopper, said jar-ring also serving to keep the guano fed well down into the bottom of the hopper at all times, rendering a stirring device unnecessary.

Having thus described a preferred embodiment of my invention, I desire it to be understood that although specific terms are employed, they are used in a generic and descriptive sense, and not for purpose of limitation, the scope of the invention being set forth in the appended claims.

20 I claim:

1. In a guano distributor and the like, a hopper secured on the framework of the distributor and having a vertically adjustable and oscillatory bottom member.
2. In a guano distributor, a hopper having an open lower end, an oscillatory bottom member secured below the said open end and being capable of vertical adjustment with relation to the said hopper.
3. In a guano distributor, a hopper having an oscillatory and vertically adjustable bottom member.
4. In a distributor for guano and other substances, a hopper having an open lower

end, an oscillatory bottom member secured below said open end, said bottom member being mounted on spirally arranged cams for adjusting the said bottom member with relation to the hopper.

5. A guano distributor having a hopper equipped with an oscillatory and vertically adjustable bottom.

6. A guano distributor having a hopper equipped with an oscillatory and vertically adjustable bottom, the vertical adjusting means comprising a cam member having a plurality of cams, projections resting on the cams and supporting the bottom member, an adjusting lever connected to the projections, and means for holding the lever in adjusted position.

7. In a guano distributor, a hopper, an oscillatory plate mounted beneath the bottom of the hopper and forming the bottom member of the hopper, said oscillatory plate being spaced from the hopper, and means for imparting oscillatory movement to the plate.

8. In a guano distributor, a hopper, the lower end of the hopper being open, a support mounted below the hopper, a cam member mounted on the support, a movable member mounted on the cam member, and a plate loosely mounted on the movable member, and means for imparting oscillatory motion to the plate.

In testimony that I claim the foregoing as my own, I have signed this specification.

EUGENE M. COLE.
